(57) CLAIM

We claim the ornamental design for a virtual and interactive advertising display, as shown and described.

DESCRIPTION

FIG. 1 is a perspective view from the back of a virtual and interactive advertising display showing our new design;

FIG. 2 is a right side view from the back thereof;

FIG. 3 is a right side view from the front thereof;

FIG. 4 is a top view thereof;

FIG. 5 is a left side view from the back thereof;

FIG. 6 is a left side view from the front thereof; and,

FIG. 7 is a bottom view thereof.

The broken lines shown in the drawings represent unclaimed portions of the virtual and interactive advertising display of our new design.
